DESIGN FOR A DOLL

Corinne Del Vecchio, St. Albans, N. Y.

Application May 19, 1944, Serial No. 113,689

Term of patent 14 years

(Cl. D34—4)

To all whom it may concern:

Be it known that I, Corinne Del Vecchio, a citizen of the United States, residing in St. Albans, in the county of Queens, city and State of New York, have invented a new, original, and ornamental Design for a Doll, of which the following is a specification, reference being had to the accompanying drawing, forming part thereof.

In the drawing:

Fig. 1 is a front view of a doll showing my new design.

Fig. 2 is a rear view thereof.

I claim:

The ornamental design for a doll, as shown.

CORINNE DEL VECCHIO.
